Primary Examiner — Karen Kearney*Assistant Examiner* — Nathan Johnston*(74) Attorney, Agent, or Firm* — Calfee, Halter & Griswold LLP(57) CLAIM

The ornamental design for a wall mounted dispenser cabinet, as shown and described.

DESCRIPTION

FIG. 1 is a perspective view of a wall mounted dispenser cabinet showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken line showing of wall mounted dispenser cabinet is included for the purpose of illustrating portions of the article and forms no part of the claimed design.

1 Claim, 4 Drawing Sheets(56)
